GUSTAV B. PETSCHE, OF YONKERS, NEW YORK.

ROTARY PUMP.

1,380,012.

Specification of Letters Patent. Patented May 31, 1921.

Application filed September 22, 1920. Serial No. 411,878.

To all whom it may concern:

Be it known that I, GUSTAV B. PETSCHE, a citizen of the United States of America, and resident of Yonkers, in the county of 5 Westchester and State of New York, have invented a certain new and useful Improvement in Rotary Pumps, of which the following is a true and exact description, reference being had to the accompanying drawings, which form a part thereof.

My invention relates to rotary pumps of the type in which the piston is actuated by an eccentric and consists of an eccentric ring with a slide extending from one side 15 thereof through a swivel block. The object of my invention is to provide a pump of this type which will be of simple and cheap construction which will, at the same time, be highly efficient in operation.

20 The nature of my improvements will be best understood as described in connection with the drawings in which they are illustrated and in which—

Figure 1 is a side elevation of my pump 25 with one of the sections of the pump casting removed and some portions including the side and swivel block shown in section on the line 1—1 of Fig. 2.

Fig. 2 is a central elevation on line 2—2 30 of Fig. 1 with the piston and slide shown in full, and

Fig. 3 is a plan view of the eccentric ring piston.

The pump cylinder is preferably formed 35 of the two sections A and A' centrally divided along the center of the cylinder, the internal periphery of which indicated at A² is concavely curved in such wise as to make linear contact with the globular surfaces of 40 the eccentric ring piston to be hereafter described. A³, A³, indicate the flat parallel side walls of the cylinder and A⁴, A⁴, indicate the clearances given in the passage connecting the cylinder with the bearing for 45 the swivel block to permit of the oscillating movements of the slide to be described. A⁵ indicates an entrance passage for the fluid; B indicates a bearing in the section A for the end of the driving shaft and B' 50 a bearing for the shaft formed in the section A', B² indicating the usual stuffing box. C and C' indicate globular bearing surfaces for the swivel block preferably divided like

the cylinder, along the line indicated at a. D and D' indicate mating circular flanges 55 extending upward from a section A and A' formed with internal and external threads, as shown. E indicates a bearing gland screwing into the flanges D and D' and formed with a bearing surface E' for the 60 top of the globular swivel block. F is a cap screwing on the external threads of the flanges D, D', and forming a receiving chamber F' from which extends the delivery pipe G. H, H, indicate the bolts for 65 securing the two sections of the cylinder casting together. I is the driving shaft to which is secured an eccentric indicated at I'. J is an eccentric ring fitting on the eccentric and having its periphery indicated at J' in 70 the form of a section of a globe. K is a slide extending from the eccentric ring J and preferably of cylindrical form, as shown. Ports K' extend from the bottom of the slide into the delivery side of the 75 cylinder and communicate with a discharge passage extending from the ports K' to a non-return valve K² normally closing this discharge passage. K³ is a spring adjusting and holding sleeve screwing into the top 80 of the slide K and L is a spring for holding the valve to its seat. M is a swivel block in which the slide K works and which works in the bearings C, C' and E'. The spring holding sleeve K³ has by preference, 85 and as shown, a slot on its top.

In operation the shaft I rotates in an anti-clockwise direction and by means of the eccentric I' rotates the eccentric ring piston which maintains a linear contact with 90 the sides of the cylinder at all times except when at the top of the stroke when there is a short interruption of contact. During the rotation of the piston the slide K moves up and down in the swivel block and oscillates through the necessary angle together with the swivel block. The fluid upon which the pump works is admitted through the port A⁵ and is then delivered through the ports K' and through the hollow slide into 100 the chamber F', the valve K² opening to permit the passage of the fluid and closing as soon as the cycle is completed.

An important feature of my invention is the formation of the eccentric ring piston 105 with its periphery in the shape of a section

of a sphere and the formation of the periphery of the cylinder with a similar curvature so as to form a line contact with the piston. This formation of the cylinder and piston particularly when the cylinder is parted along the central line *a*, greatly facilitates the machining of the parts and cheapens the production. An advantage of the same character is found in making the swivel block of a spherical form and giving, of course, corresponding form to the bearings *C*, *C'* and *E* and I would note that the adjustable bearing gland *E* is a constructive feature of value as it enables the bearing pressure on the swivel block to be nicely adjusted.

Another advantage of my described construction also leading to cheapness of manufacture is the formation of the slide in the form of a cylinder and this cylindrical form given to the slide has also an advantage in enabling me to form one of the ports and passages of the pump cylinder, preferably as shown, the delivery port and passage through the slide and to provide in the slide a non-return valve and means for adjusting its operative pressure.

Having now described my invention, what I claim as new and desire to secure by Letters Patent, is:

1. A rotary pump having a cylinder and a globular bearing for a swivel block in combination with a globular swivel block formed with a cylindrical bearing for a slide and an eccentric ring piston having a cylindrical slide extension working in the bearing in the swivel block.

2. A rotary pump having a cylinder and a globular bearing for a swivel block in combination with a globular swivel block formed with a cylindrical bearing for a slide and an eccentric ring piston having a cylindrical slide extension working in the bearing in the swivel block, said slide having formed through it a port passage for the pump.

3. A rotary pump having a cylinder and a globular bearing for a swivel block in combination with an adjustable gland bearing for the top of the swivel block, a globular swivel block formed with a cylindrical bearing for a slide and an eccentric ring piston having a cylindrical slide extension working in the bearing in the swivel block, said slide having formed through it a port passage for the pump.

4. A rotary pump having a cylinder concavely curved to make a linear contact with the convexly curved eccentric ring, in combination with a centrally disposed driving shaft and a rotary piston made up of an eccentric secured thereto, an eccentric ring the outer face of which has the form of a section of a globe and an extension from the ring forming a discharge port of the pump.

5. A rotary pump having a cylinder with its inner periphery concavely curved to form a linear contact with the concavely curved face of the piston and a globular bearing for a swivel block in combination with an eccentric ring piston the face of which is in the form of a segment of a globe and which is provided with an extension slide of cylindrical form moving in a cylindrical bearing in the swivel block.

6. A rotary pump having a cylinder formed of two sections divided along the center line of the cylinder the periphery of the cylinder being concavely curved to make a linear contact with the convexly curved eccentric ring, in combination with a centrally disposed driving shaft and a rotary piston made up of an eccentric secured thereto, an eccentric ring the outer face of which has the form of a section of a globe and a slide extending from the ring.

7. A rotary pump having a cylinder formed of two sections divided along the center line of the cylinder the periphery of the cylinder being concavely curved to make a linear contact with the convexly curved eccentric ring and said sections having also formed in them a two part globular bearing for a swivel block, in combination with a centrally disposed driving shaft and a rotary piston made up of an eccentric secured thereto, an eccentric ring the outer face of which has the form of a section of a globe and a slide extending from the ring, and a globular swivel block in which the slide works.

8. A rotary pump having a cylinder formed of two sections divided along the central line of the cylinder, the periphery of the cylinder being concavely curved to make a linear contact with the convexly curved eccentric ring and said sections having also formed in them a two part globular bearing for a swivel block, in combination with a centrally disposed driving shaft, a rotary piston made up of an eccentric secured to the shaft and an eccentric ring the outer face of which has the form of a section of a globe, a globular swivel block having a cylindrical central bearing for the slide and a cylindrical slide extending from the eccentric ring through the swivel block.

9. A rotary pump having a cylinder formed of two sections divided along the central line of the cylinder, the periphery of the cylinder being concavely curved to make a linear contact with the convexly curved eccentric ring and said sections having also formed in them a two part globular bearing for a swivel block, in combination with a centrally disposed driving shaft, a rotary piston made up of an eccentric secured to the shaft and an eccentric ring the outer face of which has the form of a section of a globe, a globular swivel block hav-

ing a cylindrical central bearing for the slide, a cylindrical slide extending from the eccentric ring through the swivel block, said slide being formed with a discharge passage 5 extending through it and a non return valve in the discharge passage of the slide.

10. A rotary pump having a cylinder and

a bearing for a swivel block in combination with a swivel block formed with a cylindrical bearing for a slide and an eccentric 10 ring piston having a cylindrical slide extension working in the cylindrical bearing in the swivel block.

GUSTAV B. PETSCHE.
